Application December 31, 1954, Serial No. 479,108

13 Claims. (Cl. 123—122)

The present invention relates to internal combustion engines and more particularly to thermostatic means for automatically controlling the induction system.

There are normally several accessories on an internal combustion engine that are preferably automatically actuated in response to the engine temperature. For example, it has been found that when an engine is operating at subnormal temperatures, a considerable amount of difficulty is experienced in properly charging the combustion chambers. This may result from inadequate evaporation of the fuel particles into the charge and/or the charge that actually reaches the combustion chambers being too lean. As a result a choke may be provided for increasing the richness of the charge and a stove for heating the charge to improve the evaporation and mixing of the fuel particles into the charge. Although thermostats have been provided for actuating such chokes and stoves, they have not accurately and reliably sensed the engine temperature. In addition, it has been the practice heretofore to employ a separate thermostat for actuating the heat valve and the choke valve. As a result these valves may move independently of each other and thus the positions of the valves may not be properly coordinated with each other.

It is now proposed to provide means which will accurately sense the engine temperature and automatically actuate the engine accessories such as the choke and stove in response to the engine temperature. This is to be accomplished by providing thermostatic means which may have a portion thereof disposed in intimate heat exchanging relation with the engine cooling system and/or a portion that is in heat exchanging relation with the engine exhaust gases. Thus the thermostatic means will provide a very accurate index of the engine temperature. Both the choke and the stove may be actuated by this means from this common thermostatic means. Consequently, the operation of the choke and stove will be correlated with each other to insure their functioning together toward a common objective. Even though the choke and stove valves may be operated by the common thermostat, they may be connected to the thermostat by a linkage system that will cause the choke and stove to become operative and/or inoperative in any desired sequence.

In the two sheets of drawings:

Figure 1 is a fragmentary side view of an engine embodying one form of the present invention with portions thereof being broken away.

Figure 2 is a very similar to Figure 1 but showing another form of the invention.

Figure 3 is an end view taken substantially along the plane of line 3—3 in Figure 2.

Figure 4 is a side view of another form of thermostatic means embodying the present invention.

Figure 5 is a side view of another form of thermostatic means embodying the present invention.

Referring to the drawings in more detail, the present invention may be adapted for actuating any suitable engine accessories in response to the engine 10 temperature.

2

However for the purposes of illustration, in the present instance it is particularly adapted for actuating control means on an engine induction system 12.

This induction system 12 may include an intake manifold 14 and a housing 16 that is mounted on top of the manifold 14. The intake manifold 14 which may be disposed on top of the engine 10 includes a plurality of distribution passages that communicate with the combustion chambers and a carburetor riser 20 that communicates with the distribution passages. A portion of the coolant jacket 22 may be provided in the manifold to contain a portion of the liquid in the cooling system. The coolant in this jacket 22 may be discharged through an outlet to be cooled by a radiator or other suitable heat exchanger.

5 A so-called downdraft carburetor 24 may be mounted on the carburetor riser 20. A fuel mixing passage 26 may extend vertically through the carburetor 24 for mixing the fuel particles with the air as it flows therethrough. A choke valve 28 may be mounted on a valve shaft 30 extending across the intake end of the fuel mixing passage 26. Thus by moving a lever 32 on the end of the shaft 30, the choke valve 28 may be rotated to vary the air-fuel ratio.

The housing 16 may be secured on top of the manifold 14 to form an air cleaner-silencer assembly that encloses both the carburetor 24 and the fuel pump 34. A filter element 36 may be horizontally disposed in the housing 16 to form an upper compartment 38 and a lower compartment 40 on the opposite sides thereof. The carburetor 24 may be disposed in the lower compartment 40 with the intake of the fuel mixing passage extending through the filter element 36 to communicate with the upper compartment 38.

An extension 42 may be formed on one wall of the housing 16 to project forwardly from the assembly and form an intake passage 44. The present intake passage 44 terminates adjacent a portion of the exhaust system such as an exhaust crossover pipe 46 that interconnects the exhaust manifolds on the opposite sides of the engine 10. A shroud 48 may be disposed in spaced relation to the crossover pipe 46 to form a heating passage 50 having the opposite ends thereof open to the atmosphere. An aperture 52 may be provided in the middle of the shroud 48 to interconnect the intake passage 44 with the heating passage 50 formed by the shroud 48.

45 The outer end of the intake passage 44 may include a rectangular opening 54 that is positioned adjacent the aperture 52 and also communicates directly with the atmosphere. A butterfly valve 56 may be secured to a pin 58 that extends horizontally across this opening 54 to rotate with the pin 58. A lever 59 may be provided on the end of the shaft 58 for moving the valve 56. When this heat valve 56 is in the closed or vertical position, the rectangular opening 54 will be closed and the intake passage 44 will be interconnected with the heating passage 50 by means of the aperture 52. Accordingly, air flowing inwardly from the opposite ends of the heating passage 50 will be heated therein by the exhaust gases in the crossover pipe 46 before the air enters the intake passage 44. Thus 60 the air will be preheated before the fuel is atomized into the charge and the amount of mixing of the fuel into the charge will, accordingly, be greatly increased.

When the heat valve 56 is in the open or horizontal position as shown in Figure 2, air may flow from the atmosphere through the opening 54. The air entering through the upper portion of the opening will flow directly into the intake and the induction system 12. The air entering through the lower portion 60 of the opening 54 will flow into the heating passage 50 and out through the opposite ends. This will not only reduce the amount of heating of the charge but it will also cool the exhaust

crossover pipe 46 and the surrounding structure to prevent excessive deterioration thereof.

In order to automatically position the choke valve 28 and the heat valve 56, thermostatic means 62 may be provided which are responsive to the engine temperature. In the embodiment shown in Figure 1, the thermostatic means 62 is disposed in a chamber 64 formed by a housing 66. This housing 66 is preferably positioned so that at least one wall of the chamber 64 is in heat exchanging relation with the coolant contained in the cooling system. Thus the temperature of the atmosphere inside of the chamber 64 will be effected by the temperature of the coolant.

A pair of tubes 68 and 70 may be provided that communicate with the chamber 64 for transferring heat from the exhaust system to the chamber 64. One end of the first tube 68 may communicate with the heating passage 50 while the opposite end communicates with the chamber 64. The second tube 70 may have one end thereof communicating with the chamber 64 while the other end projects into the fuel mixing passage 26 anterior to the choke valve 28. If the tube is properly positioned, the pressure in the tube 70 will be a function of the volume of the air flowing therethrough. Thus as the volume of the air flowing through the mixing passage 26 increases, the vacuum will also increase. Accordingly, a pressure differential will exist between the opposite ends of the tubes 68 and 70 that will result in the heated air in the heating passage 50 being drawn through the tube 68 into the chamber 64. It is therefore apparent that the temperature of the air in the chamber 64 formed by the housing 66 results from the heat transferred from the cooling jacket and the heating passage. As a result the temperature in the housing 66 will be a function of both the exhaust temperature and the coolant temperature. By varying the amount of heat transferred from each source, the effectiveness of the two temperatures may be controlled.

The thermostatic means 62 may be provided in the chamber 64 so as to be responsive to the temperature therein. As a consequence the thermostatic means 62 will give an indication of the coolant and exhaust temperatures. Although any suitable thermostatic means may be employed, in the present instance it includes a bimetallic spring 72 that is spirally disposed about a horizontal shaft 74 and has the inner end thereof secured to the shaft 74. The shaft 74 may extend through the chamber 64 with one end thereof projecting from the housing 66. A lever 76 may be secured to this end to rotate with the shaft 74. A pair of links 78 and 80 may be secured to the outer end of this lever 76 and to the levers 32 and 59 on the choke and heat valves. Thus as the spring 72 rotates the shaft 74, the choke and heat valves 28 and 56 will be opened.

Means may be provided for varying the tension of the spring 72. The outer end of the spring 72 may be secured to one arm 82 of a bell crank 84 that rotates about the shaft 74. Another arm 86 of the bell crank 84 may be connected to a piston 88 by means of a piston rod 90. This piston 88 may be reciprocably disposed in a cylinder 92 horizontally disposed in the chamber 64. The second tube 70 may communicate with the interior of this cylinder 92 for causing a partial vacuum to be applied to at least one side of the piston 88. Thus as the volume of air flowing through the induction system 12 varies, the bell crank 84 will rotate and vary the tension of the spring 72. It has been found preferable to vary the tension so that the greater the volume of air flow through the induction system 12, the wider the valves 28 and 56 will open. The cylinder 92 may communicate with the chamber 64 by means of a restricted orifice 94 or leakage past the piston and thus insure the air flowing from the heating passage 50 into the chamber 64 and out through the tube 70 to the carburetor 24.

By properly proportioning the size of the tubes 68 and 70 and the amount of heat transferred from the coolant to the chamber 64, the comparative effectiveness of the two temperatures may be varied to provide any desired co-relation therebetween. It has been found advantageous to provide enough heat transfer from the coolant to the chamber 64 to cause the spring 72 to open the valves 28 and 56 when the coolant is near normal temperature irrespective of the exhaust temperature. As a result if the engine 10 is inoperative long enough for the exhaust temperature to drop, the valves 28 and 56 will not close until the coolant temperature has also dropped. Thus the choking and heating action will not occur unless there is actually a need therefor. It should be noted that by properly positioning the levers 32, 59 and 76 and links 78 and 80, it is possible to cause the two valves to open either simultaneously or in some predetermined relationship. In the present instance it has been found preferable to so proportion the levers that the heat valve 56 will open faster than the choke valve 28. However, it should be understood that the reverse of this may be true. It may thus be seen that both the heat valve 56 and the choke valve 28 will be controlled by a common thermostatic means which are responsive to both the coolant temperature and the exhaust temperature. This will insure a consistent relationship between the two valves as well as the optimum amount of heating and choking.

Another embodiment of the present invention is shown in Figure 2. This embodiment is similar to the first one in that it is adapted to be employed on an engine 110 having an induction system 112 that includes an intake manifold 114 and a housing 116 mounted on top of the manifold 114. A portion of the cooling jacket 122 may be disposed in the manifold 114. A carburetor 124 may be disposed inside of the housing and have a fuel mixing passage 126 extending therethrough. A choke valve 128 may be mounted on a shaft 130 that extends across the inlet of the fuel mixing passage 126. A lever 132 may be secured to the end of the shaft 130 for positioning the choke valve 128.

An intake passage 144 may be provided which terminates adjacent an aperture 152 communicating with a heating passage 150 and having an opening 154 communicating with the atmosphere. A valve 156 may be mounted on a shaft 158 for opening and closing the aperture 152 and the opening 154. A lever 159 may be provided on the end of the shaft 158 for positioning the valve 156.

In this embodiment the thermostatic means 162 comprises a device containing a material with a high coefficient of thermal expansion in one end and a plunger 165 that projects from the other end. The first end may be disposed in a passage 167 that extends through one wall of the engine into the cooling jacket 122 so that the thermally responsive material will be disposed in the coolant. Thus the thermostat will be in intimate heat exchanging relation with the engine coolant. Thus even though the thermostat 162 is disposed inside of the engine, the plunger 165 will project upwardly to produce an external signal of the engine temperature. A retainer member 169 may be secured to the engine 110 to engage a collar 171 and thereby retain the thermostat in the passage 167.

A bracket 173 may project upwardly from the top of the retainer 169 to pivotally support a bell crank 175. One arm 177 of the bell crank 175 may rest on the plunger 165 while another arm 176 projects substantially vertically upwardly to receive a pair of links 178 and 180 similar to those in the first embodiment. The opposite ends of these links 178 and 180 may be connected to the levers 132 and 159 on the choke valve 128 and the intake valve 156. Thus an increase in the temperature of the coolant will cause the bell crank 175 to move in a counterclockwise direction and move both the heat valve 156 and

choke valve 128 to the open position. As pointed out above, the length of the levers 132 and 159 and the links 178 and 180 may be varied to move the valves 128 and 156 in any desired predetermined relationship to each other.

A further embodiment of the present invention is shown in Figure 4.

This embodiment like the first two is adapted to be employed on an engine 210 having an induction system with a choke valve and a heat valve. A housing 212 may be secured to the engine 210 to form a chamber 214 having at least one wall thereof in heat exchanging relation with the engine cooling system 216. A baffle 218 may be horizontally disposed inside the housing 212 to divide the chamber 214 into an upper compartment 220 and a lower compartment 222. A bi-metallic spring 224 may be spirally disposed about a shaft 226 that extends through the upper compartment 220 with the inner end thereof being secured to the shaft 226. A lever 228 may be secured to the end of the shaft 226 to rotate therewith. Thus as the spring 224 expands and contracts, it will move the lever 228. A pair of links 230 and 232 may be provided that interconnect the lever 228 with a heat valve and a choke valve. The opposite end of the spring 224 may be secured to one arm of a lever 234 that swings around the shaft 226 and is connected to a piston 236 by means of a piston rod 238. This piston 236 may be reciprocably disposed in a cylinder 240 in the upper compartment 220. The cylinder 240 may have one end thereof connected to a portion of the induction system by means of a conduit 242 and a tube 244 may interconnect the upper compartment 220 with a source of heat such as a heating passage that is in heat exchanging relation with the exhaust system. Thus hot air will be drawn into the upper compartment 220 to heat the spiral spring 224 as a function of the exhaust gas temperature, for opening and closing of the choke and heat valves. As the volume of the air flowing through the induction system varies, the piston 236 may move and vary the spring tension. Thus the valves may open more readily when there is a large volume of air flowing through the induction system.

A second thermostatic element 246 may be provided in the lower compartment 222 in heat exchanging relation with the engine cooling system 216. In the present instance this element comprises a U-shaped bi-metallic spring 248 that has one arm 250 thereof engaging the engine and the other arm 252 projecting through an opening 254 in the baffle 218. The arm 252 may be connected to one end of a stop 256 that is pivotally mounted on a pin 258 in the upper compartment 220. The opposite end of the stop 256 may be positioned to strike a shoulder 260 on the lever 234 and limit the amount of rotation in a counterclockwise direction.

When the engine coolant is cold, the spring 248 will contract and rotate the stop 256 counterclockwise. This will move the stop 256 away from the shoulder 260 and allow the lever 234 to move in either direction. Thus if the heat transferred into the upper compartment 220 from the exhaust gases is small, the spring 224 may close the choke and heat valves provided the volume of air flow in the induction system is not large enough to move the piston 236 and modify the spring's action. When the coolant becomes hot, the spring 248 will open up and move the stop 256 over to engage the shoulder 260. Thus even if the exhaust temperature is below normal, the stop 256 will prevent the thermostat closing the heat and choke valves and causing unnecessary heating.

Another embodiment of the present invention is illustrated in Figure 5. In this embodiment the thermostat 309 includes a bi-metallic spring 302 disposed in a chamber 304 formed by a housing 306. One end of the spring 302 may be secured to a shaft 308 that extends through the chamber 304 and has a lever 310 on one end thereof. A link 312 may have one end thereof connected to this

lever 310 and the other end adapted to actuate a control valve such as the choke. When the spring 302 becomes hot it will cause the lever 310 to move clockwise and when it becomes cool, it will cause the lever 310 to move counterclockwise. A pair of tubes 314 and 316 may be provided for interconnecting the chamber 304 with the induction system and a source of heat such as a heating passage which is in heat exchanging relation with the exhaust system. Thus the spring 302 may position the choke valve in response to the exhaust temperature. A piston 318 may be disposed in a cylinder 320 and connected to the opposite end of the spring 302. Thus if the tube 314 from the induction system communicates with the cylinder 320, the spring tension may be varied in response to the volume of air flowing through the induction system.

A second thermostatic element may be provided for controlling any additional valves such as the heat valve. This thermostatic element which may be of any desired variety comprises a bi-metallic U-shaped spring 322 which is disposed inside of a shield 324. One arm 326 of the spring 322 is secured to the engine to be in heat exchanging relation with the coolant in the engine cooling system 328 and the other end of this spring 322 engages one arm of a bell crank 330. A link 332 may be connected to another arm on the bell crank 330 for interconnecting the bell crank with a valve such as the heat valve.

It is thus seen that thermostatic means are provided such that if the exhaust temperature is below normal, the choke valve will be closed to enrich the fuel charge and if the coolant temperature is below normal, the heat valve will be closed to heat the incoming charge.

It has been found that when the engine is inoperative the exhaust temperature will drop considerably faster than the engine coolant temperature. Thus after the engine has been idle for a short period of time, the exhaust temperature may be low enough to cause the spring 302 to bias the choke valve to the closed position even though the engine coolant is hot. Thus an override mechanism 334 may interconnect the choke with the heat valve linkages. This mechanism 334 includes a rod 336 having a lost motion connection such as an elongated slot 338 to permit relative movement of the two valves. Thus when the engine coolant is cold, the spring 322 will allow the bell crank 330 to rotate counterclockwise and close the heat valve. This will allow the spring 302 to position the choke valve in response to the engine exhaust temperature because the slot 338 will allow the rod 336 to move.

However, when the engine coolant approaches normal operating temperatures, the bell crank 330 will rotate clockwise thereby opening the heat valve. At the same time the bell crank arm will engage the end of the slot 338 and all of the slack in the lost motion mechanism will be eliminated. Thus even though the exhaust temperature is below normal, the rod 336 will prevent the spring 322 from moving the lever 310 counterclockwise and opening the choke valve.

It is to be understood that, although the invention has been described with specific reference to particular embodiments thereof, it is not to be so limited since changes and alterations therein may be made which are within the full intended scope of this invention as defined by the appended claims.

What is claimed is:

1. In an internal combustion engine having induction means, the combination of an engine cooling system, an engine exhaust system, a choke valve for varying the air-fuel ratio of the charge in said means, a heat valve for controlling the amount of heat transferred from said systems to said charge, thermostatic means responsive to the temperatures of both of said systems and a pair of links having the first ends thereof operatively connected to said thermostatic means, the opposite end of one of said links being connected to one of said valves and the opposite

end of the other of said links being connected to the other of said valves.

2. In an internal combustion engine having induction means, the combination of an engine cooling system, an engine exhaust system, a choke valve for varying the air-fuel ratio of the charge in said means, a heat valve for controlling the amount of heat transferred from said systems to said charge, thermostatic means having a portion thereof responsive to the temperature of one of said systems and another portion responsive to the temperature of said other system, a common linkage interconnecting said valves with each other and with said thermostatic means.

3. In an internal combustion engine having induction means, the combination of an engine cooling system, an engine exhaust system, a choke valve for varying the air-fuel ratio of the charge in said means, a heat valve for controlling the amount of heat transferred from said systems to said charge, a first thermostatic element responsive to the temperature of one of said systems and a second thermostatic element responsive to the temperature in the other of said systems, a common linkage operatively interconnecting said thermostatic elements with said valves, lost motion means actuated by one of said thermostatic elements to inactivate the other of said thermostatic elements when the temperature of the system associated with said next to last mentioned thermostatic element exceeds a predetermined amount.

4. In an internal combustion engine having induction means, the combination of an engine cooling system, an engine exhaust system, a choke valve for varying the air-fuel ratio of the charge in said means, a heat valve for controlling the amount of heat transferred from said systems to said charge, a first thermostat responsive to the temperature in one of said systems, a second thermostat responsive to the temperature in the other of said systems, a pair of links having one end thereof operatively connected to one of said thermostats with the opposite end of one of said links being operatively connected to one of said valves and the opposite end of the other of said links being operatively connected to the other of said valves, stop means actuated by said second thermostat for preventing said first thermostat opening said valves when the temperature of the system associated with said second thermostat exceeds a predetermined amount.

5. In an internal combustion engine having induction means, the combination of an engine cooling system, an engine exhaust system, a choke valve for varying the air-fuel ratio of the charge in said means, a heat valve for controlling the amount of heat transferred from said systems to said charge, a first thermostat responsive to the temperature of said exhaust system, a second thermostat responsive to the temperature of said cooling system, a first link interconnecting one of said thermostats with one of said valves and a second link interconnecting the other of said thermostats with the other of said valves, lost motion means operatively interconnecting said thermostats with each other to prevent the operation of said first thermostat when the temperature of said cooling system exceeds a predetermined amount.

6. In an internal combustion engine having induction means, the combination of an engine cooling system, an engine exhaust system, a choke valve for varying the air-fuel ratio of the charge in said means, a heat valve for controlling the amount of heat transferred from said systems to said charge, a housing forming a chamber disposed in heat exchanging relation with said cooling system and said exhaust system, a thermostatic element disposed in said chamber, common linkage means operatively interconnecting said thermostatic element with said valves.

7. In an internal combustion engine having induction means, the combination of an engine cooling system, an engine exhaust system, a choke valve for varying the air-fuel ratio of the charge in said means, a heat valve

for controlling the amount of heat transferred from said systems to said charge, a housing forming a chamber, a baffle disposed in said housing and dividing said chamber into two separate compartments with one of said compartments being in heat exchanging relation with one of said systems and the other of said compartments being in heat exchanging relation with the other of said systems, a first thermostatic element disposed in the first of said compartments and being operatively connected to said valves by a common linkage, a second thermostatic element disposed in the second of said compartments and being effective to prevent the operation of said first thermostatic element when the temperature of the system associated with said second compartment exceeds a predetermined amount.

5 8. In an internal combustion engine having induction means, the combination of an engine cooling system, an engine exhaust system, a choke valve for varying the air-fuel ratio of the charge in said means, a heat valve for controlling the amount of heat transferred from said systems to said charge, a housing forming a chamber disposed in heat exchanging relation with said cooling system, duct means having one end thereof communicating with said chamber and having the other end thereof terminating adjacent said exhaust system, thermostatic means disposed in said chamber, and a common linkage operatively interconnecting both of said valves with said thermostatic means.

20 9. In an internal combustion engine having induction means, the combination of an engine cooling system, an engine exhaust system, a choke valve for varying the air-fuel ratio of the charge in said means, a heat valve for controlling the amount of heat transferred from said systems to said charge, a housing forming a chamber having one wall thereof disposed in heat exchanging relation with said cooling system, a thermostatic spring disposed in said housing, a common linkage operatively interconnecting said thermostatic spring with said valves, pneumatic means for tensioning said spring, a first duct having one end thereof communicating with said chamber and the other end thereof terminating adjacent said exhaust system, a second duct having one end thereof communicating with said induction means and the other end thereof communicating with said pneumatic means.

25 10. In an internal combustion engine having induction means, the combination of an engine cooling system, an engine exhaust system, a choke valve for varying the air-fuel ratio of the charge in said means, a heat valve for controlling the amount of heat transferred from said systems to said charge, a housing forming a chamber, a baffle disposed in said housing and dividing said chamber into two separate compartments, the first of said compartments being in heat exchanging relation with said cooling system, duct means having one end thereof communicating with said second chamber and the other end thereof terminating adjacent said exhaust system, a first thermostatic element disposed in the first of said compartments, a second thermostatic element disposed in the second of said compartments and being operatively connected to both of said valves by a common linkage, duct means having one end thereof communicating with said second chamber and having the other end thereof terminating adjacent said exhaust system, a movable stop actuated by said first thermostatic element to prevent the operation of said first thermostatic element when the temperature of said cooling system exceeds a predetermined amount.

30 11. The combination of claim 10 including pneumatic means for tensioning said second thermostatic element and second duct means having one end thereof communicating with said pneumatic means and the other end thereof communicating with said charge forming means.

35 12. In an internal combustion engine having induction means, the combination of an engine cooling system, an engine exhaust system, a choke valve for varying the air-

fuel ratio of the charge in said means, a heat valve for controlling the amount of heat transferred from said systems to said charge, a housing forming a chamber, a thermostatic spring disposed in said chamber and being operatively connected to said heat valve for moving said heat valve between on and off positions, pneumatic means in said chamber for tensioning said spring, a first duct having one end thereof communicating with said pneumatic means and the other end thereof communicating with said induction means, a second duct having one end thereof communicating with said chamber and the other end thereof terminating adjacent said exhaust system, a second thermostatic spring disposed in heat exchanging relation with said cooling system and being operatively connected to said choke valve for moving said choke valve between on and off positions, linkage means interconnecting said thermostatic springs and having lost mo-

5 10 15

tion means to prevent moving said heat valve to the on position when the temperature of said cooling system exceeds a predetermined amount.

13. In an internal combustion engine having induction means, the combination of an engine cooling system, an engine exhaust system, a choke valve for varying the air-fuel ratio of the charge in said means, a heat valve for controlling the amount of heat applied to said charge, a thermostatic element disposed in said cooling system and being responsive to the temperature thereof and a common linkage interconnecting said valves with each other and with said thermostatic element.
